GOLF CLUB HEAD

Marcel Gryseels, 21753 McCormick,
Detroit, Mich. 48236

Filed Nov. 6, 1970, Ser. No. 25,854

Term of patent 14 years

Int. Cl. D21—02

U.S. Cl. D34—5

FIG. 1 is a perspective view of a golf club head, showing my new design;

FIG. 2 is a rear elevation;

FIG. 3 is a front elevation;

FIG. 4 is an end elevation taken from the left of FIG. 3; and

FIG. 5 is an end elevation taken from the right of FIG. 3.

I claim:

The ornamental design of a golf club head, as shown.
